Filed Aug. 2, 1965, Ser. No. 86,376

Term of patent 14 years

(Cl. D30—1)

FIG. 1.

FIG. 2.

FIG. 3.

FIG. 4.

FIG. 5.

FIG. 6.

FIG. 1 is a view showing in elevation the face of a firearm recoil pad embodying my new design;

FIG. 2 is a front side elevation of FIG. 1;

FIG. 3 is a left end elevation of FIG. 2;

FIG. 4 is a right end elevation of FIG. 2;

FIG. 5 is a fragmentary enlargement of the design configuration of FIG. 1; and

FIG. 6 is a cross section on line 6-6 of FIG. 5.

The dominant features of the design reside in the solid line showing of the pad face.

I claim:

The ornamental design for a firearm recoil pad, as shown and described.
